UNITED STATES PATENT OFFICE.

PETER EPLER, OF WILLIAMSPORT, PENNSYLVANIA.

DESIGN FOR A HARNESS-HOOK.

SPECIFICATION forming part of Design No. 27,917, dated November 30, 1897.

Application filed October 6, 1897. Serial No. 654,292. Term of patent 7 years.

To all whom it may concern:

Be it known that I, PETER EPLER, a citizen of the United States, residing at Williamsport, in the county of Lycoming and State of Pennsylvania, have invented and produced a certain new and original Design for Harness-Hooks; and I do declare the following to be a full, clear, and exact description of the invention, such as will enable others skilled in the art to which it appertains to make and use the same.

My invention relates to a new and original design for harness-hooks; and it consists of a design of the configuration and ornamentation shown in the accompanying drawings, in which—

Figure 1 is a perspective view of my design. Fig. 2 is a bottom plan view. Fig. 3 is a top plan view, and Fig. 4 is a longitudinal sectional view.

The leading features of the invention comprise a rectangular frame 1, having a polygonal portion 2, and a downwardly and outwardly projecting tongue 3, the sides of which converge and the end of which projects upwardly and slightly inwardly and is located within the edges of the body portion. A stud 4 projects from the under side of the tongue near the rectangular frame inwardly at an acute angle to the frame. 25 30

What I claim is—

The design for a harness-hook, as herein shown and described.

In testimony whereof I hereunto affix my signature in presence of two witnesses.

PETER EPLER.
